CLAIM

The ornamental design for a combined shipping and storage container for syringes, as shown and described.

DESCRIPTION

FIG. 1 is a perspective view of a combined shipping and storage container for syringes showing our new design; FIG. 2 is a front elevational view thereof, the rear elevational view being identical thereto;

FIG. 3 is a side elevational view thereof, the opposite side being identical thereto;

FIG. 4 is a top plan view thereof; and

FIG. 5 is a bottom plan view thereof.
